UNITED STATES PATENT OFFICE

2,449,290

BOTTLE CAP

Pete Gavrilis, Laurel, Md.

Application January 30, 1947, Serial No. 725,213

2 Claims. (Cl. 215—45)

1

This invention relates to bottle caps and it consists in the constructions, arrangements and combinations herein described and claimed.

It is a particular object of the invention to provide a bottle cap embodying a construction somewhat similar to that shown in my Patent No. 2,392,912, but differing thereover in the provision of a simplified assembly of the cap and the securing means associated therewith.

A further important object of the invention is the inclusion of a flexing member within the cap proper so arranged as to tend to oppose seating of the cap in the neck of a bottle thus effecting a constant tension upon the securing means when engaged with the bottle, and effecting a positive gas tight seal.

A still further object of the invention is the provision of a compressible bottle closure in which slots are formed therein for reception of bail members, the slots being of such dimensions as to firmly grip and hold the bails against displacement.

Additional objects, advantages and features of invention will be apparent from the following description considered in conjunction with the accompanying drawing, wherein

Figure 1 is a perspective view of one form of the cap. Figure 2 is a fragmentary elevation partly in section of a bottle having the stopper engaged therewith in closed position.

Figure 3 is a fragmentary elevation of a bottle having the stopper engaged therewith in released position.

Figure 4 is a cross section on the line 4—4 of Figure 2.

Figure 5 is a top plan view of the cap shown in Figure 1.

Figure 6 is a cross section on the line 6—6 of Figure 5.

Figure 7 is an enlarged fragmentary cross section illustrating the connection of the bail members and the clamp.

Figure 8 is a top plan view of a modified form of the stopper.

Figure 9 is a bottom plan view of the flexible disk cap employed in the stopper.

Figure 10 is a side elevation thereof.

There is illustrated a portion of a beverage bottle 10 of conventional form, in which an annular groove 11 is formed below the mouth 12.

The cap 13 is molded from rubber or other resilient material such as certain plastics. The cap is of a diameter greater than the mouth 12 of the bottle and includes an axial stopper 14 of slight depth, and as best seen in Figure 6, the

2

peripheral edge 15 of the stopper 14 is arcuate shaped gradually merging upwardly into the cap proper.

Molded with the cap 13 and the stopper 14 there is a resilient metallic disk 16 consisting of a convex body portion 17 circumscribed by downwardly directed spaced legs 18 integrally formed with the body portion. The legs 18 lie in substantially parallel relation with the periphery of the stopper 14, which under compressive force will tend to expand the stopper 14 circumferentially into snug engagement with the mouth of the bottle, as will be more fully explained.

In the form of the cap shown in Figure 1, the cap 13 is formed with a pair of right angular channels 19 of a depth stopping above the horizontal medial portion of the cap and of a width less than the diameter of respective bail members 20, and as best seen in Figure 6, the bail members 20 are substantially U-shaped, the bight portion 21 being of a width so as to present respective leg members 22 upon opposite sides of the neck of a bottle when the cap is engaged thereon, the bight portions 21 being disposed in respective channels 19, and by reason of the greater diameter of the bail members 20, the latter will be securely retained within the channels. From the foregoing, it will be seen that the cap and bail members may be separately formed and later assembled, thus greatly simplifying manufacture of the device.

By reason of the right angular arrangement of the channels 19, the bight portion 21 of one of the bail members is formed with an open loop 21' to accommodate the bight portion of the other bail member.

The leg members 22 are each formed with an eyelet 23 at their extremities and receive a divided clamping ring 24 therethrough. The legs 22 are of such length as to position the ring 24 in the groove 11 of the bottle, for a purpose as will appear.

The ring 24 is formed with circumferentially spaced loops 25 positioned so as to receive respective eyelets 23 therewithin, and as may be seen in Figure 4, the loops 25 are outwardly disposed with respect to the bottle neck so as to accommodate the thickness of the material forming the eyelets. By interlocking the bail members and the clamping ring in this manner, the bail members are held against slippage and insuring a straight downward pull upon the cap when the latter is seated in the bottle mouth.

The ring 24 has a hook member 26 at respective ends arranged in opposed relation to one another

and receive respective eyelets 27 of a cam lever 28. The operation of the cam lever 28 is well understood in the art, and a detailed explanation is not believed necessary, except to state that when the lever is moved downwardly so as to rest upon the neck of the bottle, as in Figure 2, contraction of the ring will have been effected, drawing the ring snugly into the groove 11 of the bottle. As the ring is contracted there will be a downward pull upon the legs 22, thus drawing the stopper 14 into the mouth of the bottle. Such downward pull upon the cap will flex the disk 16, forcing the legs 18 circumferentially outward, forcing the peripheral wall 15 of the stopper firmly against the wall of the mouth 12, to effect a positive gas-tight seal.

A modified form of the stopper is illustrated in Figure 8, wherein the channels 19' are arranged in parallel relation. The parts corresponding to those previously described are indicated by primed reference characters.

While I have shown and described preferred constructions, this is by way of illustration only, and I consider as my own all such modifications in construction as fairly fall within the scope of the appended claims.

I claim:

1. The combination of a bottle having a neck and a mouth and a groove formed therebelow, a resilient cap member having a medial stopper, said cap further having a pair of channels in the upper face thereof, a bail member in each channel, said channels being of a width less than the diameter of the bail members and of a depth to enclose said bail members for a major portion of their length, each bail member having a pair of legs adapted to extend beside the neck of a bottle in opposed relation, each leg having an eyelet at its lower end, a divided ring disposed through the eyelets and having respective looped ends, said

ring normally occupying a position slightly above the groove of the bottle, cam means operatively connected with the looped ends of said divided ring for contracting and drawing the divided ring into said groove and effecting a downward pull upon said legs, and a resilient disk embedded in said cap, said disk having downwardly disposed circumferentially spaced legs adjacent the periphery of said stopper.

2. A bottle cap comprising a resilient cap having a pair of channels in the upper face thereof, a bail member disposed in each channel, said channels being of a width less than the diameter of the bail members and of a depth to enclose said bail members, whereby to hold said bail members within the channels, each bail member having downwardly extended leg portions terminating in eyelets, a divided ring engaged through respective eyelets of the leg portions and having respective looped ends and cam means operatively engaged with the looped ends of the ring for contracting the latter around the neck of a bottle and exerting a downward pull upon the leg portions of the bail members.

25 PETE GAVRILES.
